ARTHUR W. CLAUDER, OF BRIDGEPORT, CONNECTICUT, ASSIGNOR TO UNION TYPE-WRITER COMPANY, OF JERSEY CITY, NEW JERSEY, A CORPORATION OF NEW JERSEY.

TYPE-WRITING MACHINE.

1,030,503.

Specification of Letters Patent.

Patented June 25, 1912.

Application filed July 8, 1905. Serial No. 268,777.

To whom it may concern:

Be it known that I, ARTHUR W. CLAUDER, citizen of the United States, and resident of Bridgeport, in the county of Fairfield and 5 State of Connecticut, have invented certain new and useful Improvements in Type-Writing Machines, of which the following is a specification.

This invention relates to improvements in 10 the type actions of typewriting machines, it being especially applicable to visible writing machines of the style called front-strike machines.

The object of the invention is to so improve 15 the construction of the type actions as to relieve all of their parts from injurious torsional strains, to equalize the depressions of the finger keys, and to secure other benefits affecting the operation of the 20 mechanism, and includes the provision of means embodied in the type bars and type bar rest for preventing any of the type bars from rebounding into the path of another.

This invention consists of all the various 25 features of construction, combinations and arrangements of parts, which are herein-after described and specified in the appended claims.

On the accompanying sheets of drawings, 30 in which like reference numerals designate like parts in different views, Figure 1 is a side and sectional elevation of portions of a front-strike typewriting machine, including mechanism representing the invention; 35 Fig. 2 is a front and sectional elevation of some of the same and other portions of this machine, certain connecting links being indicated by single lines; and Fig. 3 is a plan of some of the finger keys and a part of the 40 mechanism operative thereby to actuate the type bars, the single lines at the left of the devices which are fully shown in plan, illustrating connecting links.

The frame of the machine is composed of 45 a rectangular body 1 on which are posts 2, and of a top-plate 3 fastened on the posts 2. The top plate has in it an opening 4 through which the type-bars move toward and from the platen 5. A type bar segment 50 6 is secured in the frame under the front of the platen. It may be attached to the top plate by screws 7 passing through lugs 8, formed on the ends of the segment, into threaded holes in the top plate as appears 55 by Fig. 2, or may be confined by other means

in its proper position in the frame. In this segment are approximately radial slots 9, whose sides if produced would extend to or close to the center of curvature of the segment at the front of the platen, or to the 60 printing point. The type bars 10 are mounted on the segment, each type bar fitting in one of the slots 9 and being secured therein by a universal pivot wire 11, which lies in a groove in the segment and passes 65 through all of the type bars. The type bars normally extend toward the front of the machine from the segment to a type bar rest 12, by which their front ends are supported. Each type bar is movable on its pivot from 70 its normal position to its printing position, the type bar which is shown in Fig. 1 being represented by dotted lines in that figure in its printing position.

In the front part of the frame of the machine are fixed two round cross rods 13 and 14, whose axes are parallel to the axis of the platen and in a vertical plane. These rods are attached at their ends to the sides of the frame. Two series of parallel angular levers 15 and 16 on which are formed hubs 17 and 18, are loosely mounted on the rods 13 and 14, the levers being arranged in pairs as shown, each of the levers 15 being over a lever 16. To each of the forwardly 85 projecting arms of each pair of these levers, these arms being of equal length, is pivoted an upright link 19, having an extension on which is a finger key 20. The extensions of the links are properly formed to secure the arrangement of the finger-keys in banks, the extensions 21 on which the finger keys of the uppermost bank are mounted being prolongations of the links on which they are formed, and the other extensions 22, 23 and 24, projecting different distances in front of the links, in rows of different heights. Since the levers 15 and 16 are parallel and the axes of the pivots 25 and 26 are equally distant from the vertical plane containing 90 the axes of the rods 13 and 14, the levers of any pair may be turned together on their pivotal axes by depressing the finger key connected with them and each link 19 turns on four axes 13, 14, 25 and 26. 100

To the rear ends of each pair of the parallel levers described is pivoted an upright link 27, comprising upper and lower arms 28 and 29 which project in front of the upright portion of the link and are pivoted re- 110

spectively to the upper and lower levers of the pair by pins 30 and 31, the upright portions of these links 27 being behind the vertical plane containing the axes of the rods 13 and 14, and lying normally close to the type bar rest 12. The links 27 therefore are likewise arranged to turn on four axes, the fixed axes or pivot rods 13 and 14 and the movable axes or pivots 30 and 31. Those links 27 which are in front of the middle portion of the type bar segment are provided with extensions 32 at their lower ends, and each of the two links at the ends of this series has on its upper end an extension 33. Connecting links 34 are pivoted at their front ends to the upright links 27 by pins 35, and at their rear ends to the type bars by pins 36. The front ends of the connecting links are pivoted to the upright links at elevations which progressively increase from the middle to the sides of the system of type actions. To each connecting link 34 is attached a restoring spring 37, which is also attached to a curved cross bar 38 fixed under the typebar-segment.

The operation of the type actions described is indicated by dotted lines in Fig. 1, which represent the positions of the parts of one of the type actions at the end of a printing movement of the type bar. With the depression of the finger key the angular levers are turned on their axes, the pivots 30 and 31 being carried toward the front of the machine on arcs whose chords are substantially horizontal, and the link 27 is drawn forward, pulling with it the connecting link 34, the result being that the type bar is swung to its printing position. It will be understood, since four of the pivotal axes of every type action are parallel to one another and the links 34 are nearly horizontal and converge but slightly from the links 27 to the type bars, that only small torsional strains will be produced either at the sides of the system or elsewhere, and it will also be seen that the dip of each finger key will substantially equal that of every other, for substantially equal movements of the links 27 are required to actuate the type bars, and that the faces of the finger keys are constantly horizontal.

The type bar rest 12 is fixed in its relations to each of the type bar pivots. In machines in which the type bar segment is movable toward and from the platen, the type bar rest is to be attached to supports 46 projecting from the segment. The face 39 of the rest, and that part 40 of the edge of the type bar which makes contact with the rest, are preferably formed and arranged as represented in Fig. 1 of the drawings, but it is not necessary that the form of either the rest or the edge of the type bar should be precisely as shown. Their relations are to be such, however, as

to render the angle of incidence of the type bar on the rest a large acute angle, whose complement is equal to the angle included by the faces of a wedge, and consequently to subject the type bar and its pivot to pressure acting lengthwise of the type bar, when the latter strikes the rest on returning to its normal position. The face 39 of the rest is shown in the form of a section of the surface of a blunt cone, whose axis is on a horizontal line 41 cutting the platen at the printing point, and whose apex is at the point 42 on the line 41, in front of a vertical plane parallel to the axis of the platen and cutting the typebar-rest. The base of this cone is, therefore, vertical and forms with any of the elements of the cone a smaller angle than is formed by the element with the axis of the cone. The relations of a type bar and the type bar rest being as they are shown in Fig. 1, the angle of incidence of the type bar on the rest is included between lines 43 and 44, the line 43 being tangent to the arc described by a point 45 on the type bar, and the line 44 being perpendicular to an element of the supposed cone, and the lines 43 and 44 intersecting each other at the point 45. This angle of incidence therefore is considerably greater than an angle of forty-five degrees, and its complement, represented by the lines 42 and 43, is equal to the angle included by the faces of a wedge. By subjecting the type bars to pressure acting lengthwise thereof as explained, each of the type bars may be prevented from rebounding into the path of another even when the machine is rapidly operated.

Various changes may be made in the mechanism above described without departing from the invention herein set forth and claimed.

What I claim as new and desire to secure by Letters Patent, is:—

1. In a typewriting machine, a type action comprising a pivoted type bar, a pair of parallel levers, a link pivoted to each of said levers and provided with an extension on which is a finger key, another link pivoted to each of said levers, and means connecting the latter link with the type bar.
2. In a typewriting machine, a type action comprising a pivoted type bar, a link pivoted to the type bar, a pair of parallel levers, a link pivoted to each of said levers and provided with an extension on which is a finger key, and another link pivoted to each of said levers and to the first-mentioned link.
3. In a typewriting machine, a type action comprising a pivoted type bar, a pair of parallel levers whose pivotal axes are at different elevations and in a vertical plane parallel to the axis of the platen, an up-

right link pivoted to each of said levers in front of said plane and provided with an extension on which is a finger key, another upright link pivoted to each of said levers behind the first mentioned link, and means connecting the rear link with the type bar.

4. In a typewriting machine, a type action comprising a pivoted type bar, a link pivoted to the type bar, a pair of parallel levers whose pivotal axes are at different elevations and in a vertical plane parallel to the axis of the platen, an upright link pivoted to each of said levers in front of said plane and provided with an extension on which is a finger key, and another upright link pivoted to each of said levers and lying behind said plane and pivoted to the first mentioned link.

5. In a typewriting machine, the combination with a rotary platen, of a type action comprising a pivoted type bar, a pair of parallel levers whose pivotal axes are at different elevations and in a vertical plane parallel to the axis of the platen, an upright link pivoted to each of said levers and lying behind said plane, a connection between said upright link and the type bar, and key-actuated means operative on said levers in front of said plane.

6. In a typewriting machine, the combination with a rotary platen, of a type action comprising a pivoted type bar, a link pivoted to the type bar, a pair of parallel levers whose pivotal axes are at different elevations and in a vertical plane parallel to the axis of the platen, an upright link pivoted to each of said levers and lying behind said plane and pivoted to the first mentioned link, and key actuated means operative on said levers in front of said plane.

7. In a typewriting machine, the combination with a rotary platen, of a type action comprising a pivoted type bar, a pair of pivoted devices whose pivotal axes are at different elevations and in a vertical plane parallel to the axis of the platen, an upright link pivoted to each of said devices and operative thereby, a connection between said link and the type bar, and means including a finger key and another link operative to actuate said pair of pivoted devices.

8. In a typewriting machine, the combination with a rotary platen, of a type action comprising a pivoted type bar, a pair of pivoted devices whose pivotal axes are at different elevations and in a vertical plane parallel to the axis of the platen, an upright link pivoted to each of said devices, a link pivoted at one of its ends to said upright link and at its other end to the type bar, and means including a finger key operative to actuate said pair of pivoted devices.

9. In a typewriting machine, the combination with a rotary platen, of a type action

comprising a type bar pivoted to a support below the platen and extending normally from its pivot toward the keyboard of the machine, a pair of pivoted devices whose pivotal axes are at different elevations, a link pivoted to each of said devices, a connection between said link and the type bar, the ends of said connection being on a line which extends lengthwise of the machine, and means including a finger key operative to actuate said pair of pivoted devices.

10. In a typewriting machine, the combination with a rotary platen, of a type action comprising a type bar pivoted to a support below the platen and extending normally from its pivot toward the keyboard of the machine, a pair of pivoted devices whose pivotal axes are at different elevations, a link pivoted to each of said devices, a link pivoted at one of its ends to the above-mentioned link and at its other end to the type bar, and means including a finger key operative to actuate said pair of pivoted devices.

11. In a typewriting machine, the combination with a rotary platen, of a type action comprising a pivoted type bar, a pair of pivoted devices secured at different elevations, a link having upper and lower arms on one side of the body of the link, these arms being pivoted respectively to said upper and lower pivoted devices, a connection between said link and the type bar, and means including a finger key operative to actuate said pair of pivoted devices.

12. In a typewriting machine, the combination with a rotary platen, of a type action comprising a pivoted type bar, a pair of pivoted devices secured at different elevations, a link having upper and lower arms on one side of the body of the link, these arms being pivoted respectively to said upper and lower pivoted devices, a link pivoted to the above-mentioned link and to the type bars, and means including a finger key operative to actuate said pair of pivoted devices.

13. In a typewriting machine, the combination with a rotary platen, of a type action comprising a pivoted type bar, a pair of parallel levers secured at different elevations, the upper lever being over the other, a link having upper and lower arms pivoted respectively to said upper and lower levers, a connection between said link and the type bar, and means including a finger key and another link operative to actuate said levers, the last mentioned link being pivoted to each of said levers.

14. In a typewriting machine, the combination with a rotary platen, of a type action comprising a pivoted type bar, a pair of parallel levers secured at different elevations, the upper lever being over the other, a link having upper and lower arms pivoted

- respectively to said upper and lower levers, a link pivoted to the above mentioned link and to the type bar, and means including a finger key and another link operative to 5 actuate said levers, the last mentioned link being pivoted to each of said levers. 70
15. In a typewriting machine, a type action comprising a pivoted type bar, a pair of parallel levers whose pivotal axes 10 are at different elevations and in a vertical plane parallel to the axis of the platen, an upright link pivoted to each of said levers in front of said plane and provided with an extension on which is a finger key, another 15 upright link lying behind said plane and having upper and lower arms pivoted respectively to the upper and lower levers, and means connecting the latter link with the type bar. 75
20. In a typewriting machine, a type action comprising a pivoted type bar, a link pivoted to the type bar, a pair of parallel levers whose pivotal axes are at different elevations and in a vertical plane 25 parallel to the axis of the platen, an upright link pivoted to each of said levers in front of said plane and provided with an extension on which is a finger key, and another 30 upright link lying behind said plane and pivoted to the first mentioned link and having upper and lower arms pivoted respectively to the upper and lower levers. 80
21. In a typewriting machine, the combination with a rotary platen, of a type action comprising the combination of a pivoted type bar, a pair of pivoted devices whose pivotal axes are at different elevations and in a vertical plane parallel to the axis of the platen, said devices having parallel arms of equal length extending in front of said plane, a link pivoted to each of said arms and provided with an extension on which is a finger key, and means connecting said devices with the type bar, said means including a part independent of said link and 85 attached to each of said devices. 90
22. In a typewriting machine, the combination with a rotary platen, of a set of type actions each comprising the combination of a pivoted type bar, a pair of pivoted devices whose pivotal axes are at different elevations and in a vertical plane parallel to the axis of the platen, said devices having parallel arms of equal length extending in front of said plane, a link pivoted to each 95 of said arms and provided with an extension on which is a finger key, and means connecting said devices with the type bar, said means including a part attached to each of said devices and the extensions of the links 100 being properly formed to secure the finger keys in banks. 105
23. In a typewriting machine, the combination with a rotary platen, of a set of type actions comprising two series of pivoted devices mounted on horizontal axes contained in a vertical plane parallel to the axis of the platen, said devices extending in front of said plane, and actuating means including finger keys operative on said devices in front of said plane. 110
24. In a typewriting machine, the combination with a rotary platen, of a set of type actions comprising two series of pivoted devices mounted on horizontal axes contained in a vertical plane parallel to the axis of the platen, said devices extending in front of said plane, and actuating means including upright links pivoted to said devices in front of said plane and having on them extensions provided with finger keys. 120
25. In a typewriting machine, the combination with a rotary platen, of a set of type actions comprising two series of pivoted devices mounted on horizontal axes con- 130

- tained in a vertical plane parallel to the axis of the platen, said devices extending in front of said plane, and actuating means including upright links pivoted to said devices in front of said plane and having on them extensions provided with finger keys, the extensions of these links being properly formed to secure the finger keys in banks.
26. In a typewriting machine, the combination with a rotary platen, of a set of type actions comprising two series of pivoted devices mounted on horizontal axes contained in a vertical plane parallel to the axis of the platen, said devices extending in front of said plane, and actuating means including upright links pivoted to said devices in front of said plane and having on them extensions provided with finger keys arranged in banks, the extensions of the links on which the finger keys of the uppermost bank are mounted being prolongations of the links, and the other extensions projecting in front of the links in rows of different heights.
27. In a front-strike typewriting machine containing a rotary platen and a type bar segment whose center of curvature is at the front of the platen, the combination with a set of pivoted type bars mounted on the segment, of type bar actuating mechanism comprising two series of pivoted devices mounted on horizontal axes contained in a vertical plane in front of the segment, and means including finger keys operative to actuate said devices.
28. In a front-strike typewriting machine containing a rotary platen and a type bar segment whose center of curvature is at the front of the platen, the combination with a set of pivoted type bars mounted on the segment, of type bar actuating mechanism comprising two series of pivoted devices mounted on horizontal axes at different elevations in front of the segment, and the actuating mechanism of each type bar including a device belonging to each of said two series of devices and means including finger keys operative to actuate said pivoted devices.
29. In a front strike typewriting machine containing a rotary platen and a type bar segment whose center of curvature is at the front of the platen, the combination with a set of pivoted type bars mounted on the segment, of type bar actuating mechanism comprising two series of levers mounted on horizontal axes contained in a vertical plane in front of the segment, and means including finger keys operative on the power arms of said levers.
30. In a front strike typewriting machine containing a rotary platen and a type bar segment whose center of curvature is at the front of the platen, the combination with a set of pivoted type bars mounted on the segment, of type bar actuating mechanism comprising two series of pivoted devices mounted on horizontal axes at different elevations in front of the segment, a series of upright links each pivoted to a device of the upper series and to a device of the lower series of pivoted devices, links pivoted to said upright links and to the type bars, and means including finger keys operative to actuate said pivoted devices.
31. In a front strike typewriting machine containing a rotary platen and a type bar segment whose center of curvature is at the front of the platen, the combination with a set of pivoted type bars mounted on the segment, of type bar actuating mechanism comprising two series of levers mounted on horizontal axes contained in a vertical plane in front of the segment, a series of upright links each pivoted to a lever of the upper series and to a lever of the lower series, links pivoted to said upright links and to the type bars, and means including finger keys operative on the power arms of said levers.
32. In a front strike typewriting machine containing a type bar segment whose center of curvature is at the front of the platen, the combination with a set of pivoted type bars mounted on the segment, of type bar actuating mechanism comprising two series of levers mounted on horizontal axes contained in a vertical plane in front of the segment, a series of upright links each pivoted to a lever of the upper series and to a lever of the lower series, links pivoted to said upright links and to the type bars, and another series of upright links provided with extensions on which are finger keys, each of the latter links being pivoted to a lever of the upper series and to a lever of the lower series.
33. In a front strike typewriting machine containing a rotary platen and a type bar segment whose center of curvature is at the front of the platen, the combination with a set of pivoted type bars mounted on the segment, of type bar actuating mechanism comprising a series of upright links extending above the lowest part of the segment, each of said links being arranged to turn on four axes, and two of said axes being fixed in the same vertical plane, and links pivoted to said upright links and to the type bars.
34. In a front strike typewriting machine containing a rotary platen and a type bar segment whose center of curvature is at the front of the platen, the combination with a set of pivoted type bars mounted on the segment, of type bar actuating mechanism comprising a series of upright links between the segment and keyboard, each of said links being arranged to turn on four axes, and two of said axes being fixed in the same vertical plane, and links pivoted to said upright links and to the type bars.
35. In a front strike typewriting machine

- containing a rotary platen and a type bar segment whose center of curvature is at the front of the platen, the combination with a set of pivoted type bars mounted on the segment, of type bar actuating mechanism comprising a series of upright links each arranged to turn on four horizontal axes, the elevation of each of said four axes differing from that of any other, and two of said axes being fixed in the same vertical plane, and links pivoted to said upright links and to the type bars.
36. In a typewriting machine, a type action comprising an upright link arranged to turn on four horizontal axes, two of said axes being fixed in the same vertical plane, and the others being movable in directions more nearly horizontal than vertical.
37. In a typewriting machine, a type action comprising a pivoted type bar, an upright link arranged to turn on four horizontal axes, two of said axes being fixed in the same vertical plane, and the others being movable in directions more nearly horizontal than vertical, and a link pivoted to said upright link and to the type bar.
38. In a front strike typewriting machine containing a rotary platen and a type bar segment whose center of curvature is at the front of the platen, the combination with a set of pivoted type bars mounted on the segment, of type bar actuating mechanism comprising a series of upright links extending above the lowest part of the segment, each of said links being arranged to turn on four horizontal axes, two of said axes being fixed in the same vertical plane, and the others being movable in directions more nearly horizontal than vertical.
39. In a front-stroke typewriting machine containing a rotary platen and a type bar segment whose center of curvature is at the front of the platen, the combination with a set of pivoted type bars mounted on the segment, of type bar actuating mechanism comprising a series of upright links between the segment and keyboard, each of said links being arranged to turn on four horizontal axes, two of said axes being fixed in the same vertical plane, and the others being movable in directions more nearly horizontal than vertical.
40. In a front-strike typewriting machine containing a rotary platen and a type bar segment whose center of curvature is at the front of the platen, the combination with a set of pivoted type bars mounted on the segment, of type bar actuating mechanism comprising a series of upright links, each arranged to turn on four horizontal axes, two of said axes being fixed in the same vertical plane, and the others being movable in directions more nearly horizontal than vertical.
41. In a front-strike typewriting machine containing a rotary platen and a type bar segment whose center of curvature is at the front of the platen, the combination with a set of pivoted type bars mounted on the segment, of type bar actuating mechanism comprising a series of upright links, each arranged to turn on four horizontal axes, two of said axes being fixed in the same vertical plane, and the others being movable in directions more nearly horizontal than vertical, and links pivoted to said upright links and to the type bars, those ends of the last mentioned links which are secured to the upright links being at elevations progressively increasing from the middle to the sides of the system.

42. In a front-strike typewriting machine containing a rotary platen and a type bar segment whose center of curvature is at the front of the platen, the combination with a set of pivoted type bars mounted on the segment, of type bar actuating mechanism comprising a series of upright links between the segment and keyboard, each of said links being arranged to turn on four horizontal axes, two of said axes being fixed in the same vertical plane, and the others being movable in directions more nearly horizontal than vertical, and connecting links pivoted at their front ends to the upright links and at their rear ends to the type bars, the front ends of these connecting links being at elevations progressively increasing from the middle to the sides of the system.
43. In a front-strike typewriting machine containing a rotary platen and a type bar segment whose center of curvature is at the front of the platen, the combination with a set of pivoted type bars mounted on the segment, of type bar actuating mechanism comprising a series of upright links between the segment and keyboard, each of said links being arranged to turn on four horizontal axes, two of said axes being fixed in front of a vertical plane parallel to the axis of the platen and cutting the type bar rest, and the others being movable in directions more nearly horizontal than vertical.
44. In a front-strike typewriting machine containing a rotary platen and a type bar segment whose center of curvature is at the front of the platen, the combination with a set of pivoted type bars mounted on the segment, of type bar actuating mechanism comprising a series of upright links between the segment and keyboard, each of said links being arranged to turn on four horizontal axes, two of said axes being fixed in front of a vertical plane parallel to the axis of the platen and cutting the type bar rest, and connecting links pivoted at their front ends to the upright links and at their rear ends to the type bars, the front ends of these connecting links being at elevations pro-

gressively increasing from the middle to the sides of the system.

45. In a front-strike typewriting machine containing a type bar segment whose center of curvature is at the front of the platen, the combination of a set of pivoted type bars mounted on the segment and normally extending forward therefrom, and a type bar rest secured at the front ends of the type bars in fixed relations to the type bar pivots, the face of the rest and those surfaces on the type bars which make contact with the rest being properly formed and arranged to subject each type bar to pressure acting lengthwise of the type bar, substantially as and for the purpose described.

46. In a front-strike typewriting machine containing a type bar segment whose center of curvature is at the front of the platen, the combination of a set of pivoted type bars mounted on the segment and normally extending forward therefrom, and a type bar rest secured at the front ends of the type bars in fixed relations to the type bar pivots, the face of the rest and those surfaces on the type-bars which make contact with the rest being properly formed and arranged to subject the pivot of each type bar to pressure, reacting through the type bar on the rest, substantially as and for the purpose described.

47. In a front-strike typewriting machine containing a type bar segment whose center of curvature is at the front of the platen,

the combination of a set of pivoted type bars mounted on the segment and normally extending forward therefrom, and a type bar rest secured at the front ends of the type bars in fixed relations to the type bar pivots, the face of the rest and those surfaces on the type bars which make contact with the rest being properly formed and arranged to subject each type bar to pressure between the type bar rest and the pivot of the type bar, substantially as and for the purpose described.

48. In a front-strike typewriting machine containing a type bar segment whose center of curvature is at the front of the platen, the combination of a set of pivoted type bars mounted on the segment and normally extending forward therefrom, and a type bar rest secured at the front ends of the type bars in fixed relations to the type bar pivots, the face of the type bar rest being a section of the surface of a blunt cone whose apex is in front of a vertical plane parallel to the axis of the platen and cutting the type bars transversely from side to side of the set.

Signed at the borough of Manhattan, city of New York, in the county of New York, and State of New York, this 6th day of July
